UNITED STATES PATENT OFFICE

146,926

DESIGN FOR A SHOWCASE

Joseph B. Platt, New York, N. Y., assignor to Stephen F. Whitman & Son, Inc., Philadelphia,
Pa.

Application March 20, 1946, Serial No. 127,689

Term of patent 14 years

(Cl. D80—11)

To all whom it may concern:

Be it known that I, Joseph B. Platt, a citizen of the United States, residing at 16 East 52nd Street, New York 22, in the county of New York and State of New York, have invented a new, original, and ornamental Design for a Showcase, of which the following is a specification, reference being had to the accompanying drawing, forming part thereof.

The drawing is a perspective view of a showcase showing my new design.

I claim:

The ornamental design for a showcase, as shown and described.

JOSEPH B. PLATT.
